(57) **CLAIM**

We claim the ornamental design for a beverage container, as shown and described.

DESCRIPTION

FIG. 1 is a perspective view of a beverage container according to the new design;

FIG. 2 is a rear view of the beverage container shown in FIG. 1;

FIG. 3 is a front view of the beverage container shown in FIG. 1;

FIG. 4 is a left side view of the beverage container shown in FIG. 1, the right side view being a mirror image thereof;

FIG. 5 is a top view of the beverage container shown in FIG. 1; and,

FIG. 6 is a bottom view of the beverage container shown in FIG. 1.

Features shown in broken lines in the drawings are not part of the claim.
